AIR CONDITIONING ATTACHMENT FOR
AUTOMOBILESRoger G. Webster, Long Beach, Calif., assignor to
Blanche S. Webster, Long Beach, Calif.

Application November 14, 1938, Serial No. 240,382

5 Claims. (Cl. 261—92)

The present invention relates to air conditioning attachments for automobiles and similar vehicles, and has for its primary object to provide a device of this character which is detachably secured to the window of the vehicle and including a rotor arranged for partial submersion in a receptacle containing water, and arranged to cause the passage of air through the saturated walls of the rotor into the interior of the vehicle to humidify and cool the same.

An important object of the present invention is to provide an attachment of this character embodying novel means to cause the rotation of the rotor to maintain the same in a saturated condition.

A still further object is to provide a device of this character of simple and practical construction, which is efficient and reliable in performance, relatively inexpensive to manufacture and which can be installed in operative position upon the window of a vehicle without necessitating any changes or alterations in the construction thereof, and which is otherwise well adapted for the purpose for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a side elevational view of an automobile window showing the air conditioning attachment in position thereon.

Figure 2 is an end elevational view of the attachment showing the same mounted in position on the window.

Figure 3 is a transverse sectional view.

Figure 4 is a longitudinal horizontal sectional view.

Figure 5 is a longitudinal vertical sectional view.

Figure 6 is a fragmentary sectional view of the discharge throat, and

Figure 7 is a perspective view of one of the deflectors mounted in the throat.

Referring now to the drawings in detail, wherein for the purpose of illustration I have disclosed a preferred embodiment of the invention, the numeral 5 designates a casing generally which is closed at one end by a rear wall 6, the other end of the casing having a lower front wall 7 and provided with a funnel 8 above the front wall for admitting air into the casing.

Extending longitudinally of the casing and supported at its ends by the rear wall 6 and front

wall 7, is a rod 9 upon which a rotor indicated generally at 10 is mounted for free rotation. The rotor is of generally cylindrical form and closed at its rear end by a rear end wall 11, the side walls of the rotor being formed of concentrically spaced foraminous material 12, preferably formed of wire screening, to form inner and outer walls and between which is positioned a loose filler 13, such as excelsior or the like. The front end of the rotor is open and the inner end of the funnel 8 is inserted into the open end thereof for admitting air directly into the interior of the rotor.

The end wall 11 of the rotor is formed with an opening 14 through which the rod 9 is inserted for rotatably supporting the rear end of the rotor 15 and adjacent the front end of the rotor and positioned between the inner and outer walls thereof is an annular spacing ring 15 and to diametrically opposite sides of which is secured the opposite ends of a tubular member 16 positioned transversely within the rotor and having an opening 17 in its intermediate portion through which the rod 9 is also freely inserted to rotatably support the forward end of the rotor on said rod.

A longitudinally extending opening 18 is formed in one of the side walls of the casing to form a discharge throat, the ends of the opening 18 being formed with extensions 19 and the top of the opening being formed with an extension 20 and cooperating with the extension 19 to form 30 a hood for the throat. The bottom edge of the opening is provided with a downturned lip 21 forming an inverted channel 22 with the adjacent side wall of the casing and adapted to accommodate the upper edge of a window 23 of an automobile or other vehicle body 24, whereby to support the casing upon the upper edge of said window with the casing properly positioned outside of the window and the throat 18 projecting into the interior of the vehicle, as will be clearly apparent from an inspection of Figure 2 of the drawings.

A plurality of deflectors 25 are secured to the top of the casing by bolts 26, the deflectors being substantially of angle iron form including the 45 flange 27 through which the bolts 26 are inserted at an intermediate portion of the flange whereby to pivotally support the deflectors in the top of the casing. The deflectors extend transversely of the casing with their inner ends overlying the 50 upper surface of the rotor, as clearly shown in Figure 3 of the drawings, and with their outer ends projecting through the throat and terminating at the open end thereof. By pivotally adjusting the deflectors on the supporting bolts 26, air 55

discharged from the throat may be directed in a desired manner into the interior of the vehicle. With the device mounted in position as shown in Figure 2 of the drawings, and with the funnel 8 positioned in a forward direction, the movement of the vehicle will force air into the rotor 12 and out through the side walls thereof through the throat 18 for discharge into the vehicle. The bottom of the casing 5 is adapted to contain a suitable quantity of water in which the lower edge of the rotor is submerged, whereby the filler 13 will become saturated and as the air is forced through the saturated filler the same will become cool by reason of the evaporation of the moisture therein.

In order to maintain all parts of the rotor in a moistened condition suitable means is provided for rotating the rotor upon the rod 9 which includes an endless cord 28 which has a portion wound once completely around the rotor as shown at 29 and separate flights of the cord 30 and 31 are fed through tubular guides 32 positioned in the throat 18, the cord terminating in a loop 33 positioned on the inside of the window in convenient position for manipulation by a person in a manner as will be apparent.

It is believed the details of construction and manner of operation of the device will be readily understood from the foregoing without further detailed explanation.

Having thus described the invention, what I claim is:

1. An air conditioning attachment for vehicles comprising a casing having an air intake opening at one end provided with an inwardly extending funnel and an air discharge opening in one side wall, said casing being adapted to contain a quantity of water, means for rotatably supporting a porous rotor at one end and at an intermediate portion in a partially submerged condition in the casing said funnel projecting into the rotor at its other end and means for supporting the casing on the upper edge of a window of the vehicle.

2. An air conditioning attachment for vehicles comprising a casing having an air intake opening at one end provided with an inwardly extending funnel and an air discharge opening in one side wall, said casing being adapted to contain a quantity of water, means for rotatably supporting a porous rotor at one end and at an intermediate portion in a partially submerged

condition in the casing said funnel projecting into the rotor at its other end, means for supporting the casing on the upper edge of a window of the vehicle and means for rotating the rotor.

3. An air conditioning attachment for vehicles comprising a casing having an air intake opening at one end provided with an inwardly extending funnel and an air discharge opening in one side wall, said casing being adapted to contain a quantity of water, means for rotatably supporting a porous rotor at one end and at an intermediate portion in a partially submerged condition in the casing said funnel projecting into the rotor at its other end, means for supporting the casing on the upper edge of a window of the vehicle and flexible means for manually rotating the rotor.

4. An air conditioning attachment for vehicles comprising a casing having an air intake opening at one end and an air discharge opening in one side wall, said casing being adapted to contain a quantity of water, means for rotatably supporting a porous rotor in a partially submerged condition in the casing, means for supporting the casing on the outside of the vehicle with the discharge opening inwardly thereof and flexible operating means for the rotor including a circumferentially extending portion surrounding the rotor and an operating end extending into the vehicle.

5. An air conditioning device for motor vehicles comprising a casing provided with an outlet passage along one side thereof for fitting a window opening of a motor vehicle, said casing having an open forward end, a funnel shaped member mounted in said end and extending inwardly thereof, a drum rotatably mounted in said casing and having an open forward end communicating with the inner end of said funnel member, said drum having an absorbent porous annular wall, a pan formed in the bottom of said casing for containing water and into which a portion of said drum extends, the forward end of said casing extending toward the front of the vehicle whereby air will be directed inwardly through said funnel shaped member and into the drum during the forward motion of the vehicle, and means for rotating said drum for moistening its porous wall to cool and cleanse the air passing through said wall to said outlet passage.

ROGER G. WEBSTER.
